UNITED STATES PATENT OFFICE.

CHARLES W. MORDEN, OF PORTLAND, OREGON.

CONSECUTIVE-SHEET PACKAGE OF REVERSELY-FOLDED MATERIAL.

1,307,139.

Specification of Letters Patent. Patented June 17, 1919.

Application filed April 26, 1917. Serial No. 164,720.

To all whom it may concern:

Be it known that I, CHARLES W. MORDEN, a citizen of the United States, and a resident of the city of Portland, county of Multnomah, State of Oregon, have invented a certain new and useful Improvement in Consecutive-Sheet Packages of Reversely-Folded Material, of which the following is a specification.

10 The object of my invention is to provide an improved package for toilet paper, toweling, and similar articles; that is to say, putting up such articles in a form of package cheap to manufacture, and especially adapted 15 for use in an inexpensive fixture, such, for example, as illustrated in the patent granted to me May 9, 1916, numbered 1,182,296.

Another object of my invention is to provide a package so arranged as to feed the 20 outer sheets forward automatically, that is, by gravity.

The details of my invention, and the construction of the strip of paper used for making my package, and the mode of forming 25 the latter are more readily understood from the description of the accompanying drawings, in which:

Figure 1 shows diagrammatically a side-edge elevation of a strip of paper creased 30 and divided into partially severed sheets so as to be adapted for forming my package;

Fig. 2 is a top view of the strip of paper shown in Fig. 1;

Fig. 3 is a diagrammatic side elevation 35 showing the result of reversely folding the sheets as illustrated in the preceding views;

Fig. 4 is a side elevation of a package made up from said strip of paper and folded as mentioned;

40 Fig. 5 is a front elevation of the package shown in Fig. 4;

Fig. 6 is a detail showing a modified arrangement of the transverse slits between the notches in the sides of the paper strip, by 45 which slits the strip is partially cut into sheets; and

Fig. 7 is a perspective view of my package of paper, supported in said inexpensive fixture provided by me.

50 The package of paper, *a*, consists of a continuous strip reversely creased at *a'* so as to form folds *b*, *c*, when the paper is folded. When the package is to assume a parallelogrammic shape, the creases *a'* are alternately 55 spaced farther apart and brought nearer to-

gether, so that the folds will be stepped progressively as represented by Figs. 3 and 4. The creasing required to produce this result is made by suitable mechanism which it is not necessary to specifically describe. It 60 suffices to say that it comprises coöperating creaser rolls and creaser blades, in which the latter are arranged to produce the effect stated. Of course, in order to obtain the parallelogrammic form of package a rectangular package could be so flexed and manipulated by hand as to cause it to assume such form; but I prefer to obtain the parallelogrammic form by the above described means. 65

The strip is divided into a plurality of 70 partially severed sheets by means of slits or perforations *d*. Notches *e* are cut in the sides of the folds, in alinement with said perforations *d*, which notches, when the strip of folded paper is compressed into 75 package form, provide diagonal grooves at the sides of the package for receiving the supporting members of a wall fixture of the type illustrated in Fig. 7, and comprising a pair of downwardly inclined parallel supporting arms *i*, and a front piece or keeper *j*, held in place by the inturned ends *i'* of the arms *i* of the wall fixture. Further details of this fixture are given in my above mentioned Letters Patent. 85

Instead of single, long slits *d*, the connected sheets of the folded strip may be partially severed by a plurality of shorter slits *g'*, as shown in Fig. 6. When the free end *h* (see Fig. 4) of the overlying fold *b* of a 90 sheet folded down from the top is pulled forward, such sheet may be easily torn from the strip, because of its being partially severed by the slit *d*. Another free end *h'* of the sheet *c*, folded up from the bottom, will 95 then project, which may be detached from the strip in the same manner. As shown by Fig. 2 and diagrammatically represented in Fig. 3, by the dotted line *s*, *s*, the slits or perforations *d* divide the package into a plurality of consecutive folded sheets partially severed from each other and alternately located at the top and the bottom of the package. Back of the package, on the arms *i* is placed a sheet of heavy cardboard *k*. The 105 inclination of the arms *i* causes a forward feed of the paper by gravitation. The inturned ends *i'* of the arms *i* facilitate the tearing off of a sheet from the package, and the described construction of my package 110

will cause the act of tearing off a sheet to project the free end of the following sheet.

It is to be noted that, as shown in Fig. 2, the slits *d* are located at one and the same side of the medial line between the creases of the consecutive folds. By this arrangement three advantages are obtained: first, there will always be projected a tab as *h* or *h'*, Fig. 4, convenient for seizing; second, after the package is formed the slits *d* of the alternate sheets will not register with each other, (see Figs. 5 and 6) therefore the sheets underlying the outermost sheet of the package cannot be torn out with such overlying sheet, and waste as well as disarrangement of the delivery operation of the package, co-operatively with its supporting fixture, is prevented; third, the described staggered arrangement of the slits will have the effect of both stiffening and strengthening the package at its weakest point, namely where the slits *d* occur.

It is self evident that my package may be formed of two or more superimposed strips as *a*, so as to obtain a delivery of two or more sheets instead of only one when a unit of the package is removed.

I claim:

1. A package consisting of a continuous strip of material reversely folded into a plurality of folds and having perforations extending transversely and approximately midway between the creases of said folds, thereby dividing said strip into a plurality of consecutive folded sheets or units partially severed from each other and alternately located at the opposite ends of the package.

2. A package consisting of a continuous strip of material reversely folded into a plurality of folds and having perforations extending transversely and approximately midway between the creases of said folds, thereby dividing said strip into a plurality of consecutive folded sheets or units partially severed from each other and alternately located at the opposite ends of the package, the creases of the folds being alternately spaced farther apart and nearer together, for the purpose set forth.

3. A package consisting of a continuous strip of material reversely folded into a plurality of folds and having perforations extending transversely and approximately midway between the creases of said folds, thereby dividing said strip into a plurality of consecutive folded sheets or units partially severed from each other and alternately located at the opposite ends of the package, and the sides of the folds having notches approximately alined with said perforations, said notches constituting grooves

for receiving the supporting members of a wall fixture.

4. A package consisting of a continuous strip of material reversely folded into a plurality of folds, the sides of the folds being made with notches constituting grooves for receiving the supporting members of a wall fixture, the alternate creases of the folds being arbitrarily spaced farther apart and nearer together, thereby bringing said notches of the sides in oblique alinement, causing the package to assume substantially the shape described, and tending to cause a forward feed by gravity.

5. A package consisting of a continuous strip of material reversely folded into a plurality of folds and having perforations extending transversely and approximately midway between the creases of said folds, thereby dividing said strip into a plurality of consecutive folded sheets or units partially severed from each other and alternately located at the opposite ends of the package, the creases of the folds being alternately spaced farther apart and nearer together, for the purpose set forth, and the sides of the folds having notches approximately alined with said perforations, said notches constituting grooves for receiving the supporting members of a wall fixture.

6. A package consisting of a continuous strip of material reversely folded into a plurality of folds and having perforations extending transversely and approximately midway between the creases of said folds, thereby dividing said strip into a plurality of consecutive folded sheets or units partially severed from each other and alternately located at the opposite ends of the package, said transverse perforations being located at one and the same side of the medial line between the creases of said folds, for the purpose set forth.

7. A package consisting of a continuous strip of material reversely folded into a plurality of folds and having perforations extending transversely and approximately midway between the creases of said folds, thereby dividing said strip into a plurality of consecutive folded sheets or units partially severed from each other and alternately located at the opposite ends of the package, said transverse perforations being located at one and the same side of the medial line between the creases of said folds, for the purpose set forth, and the sides of the folds having notches approximately alined with said perforations, said notches constituting grooves for receiving the supporting members of a wall fixture.

CHARLES W. MORDEN.
